HOOKED RUG MAKING DEVICE

Joseph A. Bolger, Philadelphia, Pa.

Application February 27, 1950, Serial No. 146,532

3 Claims. (Cl. 112—80)

1

This invention relates to new and useful improvements and structural refinements in devices for making hooked rugs, and the principal object of the invention is to facilitate convenient and expeditious insertion or threading of yarn through woven fabric so as to form a series of loops which eventually cover the entire fabric and coat therewith to provide the rug.

One of the important features of the invention resides in the provision of means for propelling or advancing the device at proper intervals along the surface of the work in response to the reciprocating movement of a yarn needle, while another feature of the invention resides in the provision of means for removably retaining the yarn needle in position, so that several needles threaded with yarn of different colors and thicknesses may be selectively used for the formation of different patterns in the rug.

Some of the advantages of the invention reside in its simplicity of construction, in its efficient and expeditious operation, and in its ability to produce hand made work as distinguished from work done by a power driven machine.

With the above more important objects and features in view and such other objects and features as may become apparent as the specification proceeds, the invention consists essentially of the arrangement and construction of parts as illustrated in the accompanying drawings, in which:

Figure 1 is a rear elevational view of the invention with the needle thereof in a projected position;

Figure 2 is a side elevational view of the subject shown in Figure 1;

Figure 3 is a side elevational view, similar to that shown in Figure 2, but illustrating the device with the needle thereof in its retracted position;

Figure 4 is a side elevational view, taken in the direction of the arrow 4 in Figure 1;

Figure 5 is an enlarged vertical sectional view, taken substantially in the plane of the line 5—5 in Figure 2;

Figure 6 is a transverse sectional detail, taken substantially in the plane of the line 6—6 in Figure 5;

Figure 7 is a perspective view of the frame used in the invention;

Figure 8 is a fragmentary side elevational view of a modified embodiment of the invention; and

Figure 9 is a perspective view of a leaf spring and pivot element used in the embodiment of Figure 8.

2

Like characters of reference are employed to designate like parts in the specification and throughout the several views.

Referring now to the accompanying drawings in detail, more particularly to Figures 1—7, inclusive, the invention consists of a hooked rug making device which is designated generally by the reference character 10 and embodies in its construction a vertically elongated frame 12 preferably assuming the form of a strap having horizontally angulated upper and lower end portions 14, 16, respectively, the lower end portion 16 of the frame being provided with an aperture 18 while another aperture 20 provided in the upper end portion 14 accommodates a fastening element 22 for securing a suitable handle 24 to the frame.

A carrier consisting of a flat strap 26 is reciprocable vertically on the inner surface of the frame 12 which is achieved by providing the carrier with a pair of studs or rivets 28 slidable in a vertical slot 30 with which the frame 12 is formed.

A pair of resilient clamps 32 are secured at vertically spaced points as at 34 to the carrier 26 and are adapted to frictionally engage a removable, tubular needle 36 which has a diametrically reduced lower end portion 38 projectable downwardly through the aforementioned aperture 18 beyond the lower end portion 16 of the frame 12.

The tubular needle 36, 38 is adapted to have the yarn 40 extended therethrough as shown in Figures 1 and 4 and if desired, an apertured tensioning bracket 42 may be provided on the carrier 26 so that the yarn may pass through it before entering the upper end of the needle, substantially as shown.

It is to be noted that by virtue of the resilient clamps 32, the needle may be readily removed and replaced by another having a yarn of a different color or thickness threaded therethrough.

Reciprocation of the carrier 26 and of the associated needle is effected by a crank handle 44 secured to a shaft or pin 46 which is rotatably journaled in the frame 12 and also carries a crank 48, the latter being provided with a plurality of apertures 50 to selectively receive a pivot pin 52 provided at the upper end of a pitman arm 54. The lower end portion of this arm is pivotally connected as at 56 to the carrier 26 so that by simply rotating the hand crank 44 the carrier together with the associated needle may be reciprocated between projected and retracted positions, as shown in Figures 2 and 3, respectively.

Moreover, by simply placing the pivot element 52 in the different apertures 50, the extent or stroke of the reciprocating movement of the carrier and needle may be varied as required.

When the invention is placed in use, the lower end portion 16 of the frame 12 is adapted, of course, to engage the work, and the invention also includes means for propelling or advancing the device along the surface of the work each time the needle is reciprocated.

These means consist of what may be called a shoe 58 which is pivotally mounted as at 60 on the frame 12 adjacent the portion 16, and is provided with a plurality of teeth 62 which engage the work and cause the device to advance each time the needle portion 38 is retracted upwardly from the fabric.

Oscillation of the shoe 58 is effected by means of a link 64 which is pivoted as at 66 to the shoe and is provided with a longitudinally extending slot 68 to slidably receive a pivot element or stud 70 which is rigidly secured to the carrier 26 and projects outwardly through the slot 30 of the frame 12.

The slot 68 is of such length that the stud 70 abuts the end of the slot and reciprocates the link 64 only at the upper end of the stroke of the carrier 26, that is, while the lower portion 38 of the needle 36 is retracted upwardly through the aperture 18. In other words, when the crank handle 44 is rotated so as to slide the carrier 26 and the needle thereon downwardly through the fabric, the link 64 is stationary and the shoe 58 is substantially in the position shown in Figures 2 and 4. However, when the needle travels upwardly and almost reaches the upper end of its stroke, the link 64 is slid upwardly by the stud 70, thus causing the shoe 58 to swing downwardly to the position shown in Figure 3 so as to advance the entire device along the surface of the work. The magnitude of the advancement or step may be varied by simply holding the device at different angles from the perpendicular, and needless to say, as soon as the needle again commences its downward travel, the shoe 58 is swung upwardly to its inactive position.

In the modified embodiment of the invention illustrated in the accompanying Figures 8 and 9, a shoe 72 is substituted for the shoe 58, the shoe 72 also being of an oscillatory nature and being pivoted to the frame 12 by a stud 74. However, the shoe 72 is of such dimensions as to extend forwardly as well as rearwardly from the frame 12 and is provided with two sets of teeth 76, 78.

The shoe 72 is provided with an arcuate slot 80 which is concentric with the stud 74 and terminates at the ends thereof in enlarged portions or apertures 82, 84, the slot 80 being adapted to slidably receive a diametrically reduced shank 86 provided at one end of a pivot element 88 which is secured to the free end portion of a leaf spring 90. The latter is also formed with an aperture 92 for pivotal mounting on the aforementioned stud 74 and the shank 86 and the pin 88 extend through an aperture (not shown) provided in the lower end portion of the aforementioned link 64, whereby the link is operatively connected to the shoe 72.

The diameter of the main body portion of the pin 88 is such as to fit in the apertures 82, 84, so that when the pin 88 is in the aperture 82 as shown in Figure 8, the teeth 76 of the shoe 72 may engage the work so as to propel the device forwardly, that is, in the direction of the

arrow 92. However, by simply pulling the main body portion of the pin 88 out of the aperture 82 and sliding the shank 86 through the slot 80 so that the pin 88 may be inserted in the aperture 84, the shoe 72 will be swung in an anti-clockwise direction, so that the teeth 78 may engage the work and propel the device rearwardly as indicated at 94. It is to be noted that the sliding of the shank 86 through the slot 80 may be effected without disconnecting the link 64 from the pin 88.

It is believed that the advantages and use of the invention will be clearly understood from the foregoing disclosure and, accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a hooked rug making device, the combination of a frame comprising a vertically elongated strap having a horizontally angulated lower end portion adapted to engage the work and provided with an opening, a handle at the upper end of said frame, a rotatable actuating crank mounted intermediate the ends of said strap, a portion of the strap below said crank being provided with a vertical slot, a reciprocable carrier comprising a second relatively short strap disposed at one side of the first-mentioned strap and having detent means thereon extending through said slot whereby the carrier is vertically slidable on the frame, an arm operatively connecting said crank to said carrier for reciprocating the latter, a clamp provided on said carrier, a vertically elongated needle frictionally held in said clamp and projectable through said opening, a fulcrum pin provided on the lower portion of said frame, an oscillatory work-engaging shoe mounted on said fulcrum pin and having a lower edge portion provided with a set of work engaging teeth, a stud provided on said carrier, and a link operatively connecting said stud to said shoe, whereby the latter may be oscillated by reciprocation of the carrier.

2. The device as defined in claim 1 together with a yarn tensioning and guiding eye provided on said carrier adjacent said needle.

3. The device as defined in claim 1, wherein said shoe extends forwardly and rearwardly from said frame, together with a pivot element connecting said link to said shoe, and means for varying the location of said pivot element relative to the shoe whereby the frame may be propelled selectively in forward and rearward directions.

JOSEPH A. BOLGER.
